Primary Examiner—Louis B. Zarfas*Assistant Examiner*—I Simmon*Attorney, Agent, or Firm*—Kelly Bauersfeld Lowry & Kelley, LLP[57] **CLAIM**

The ornamental design for a flexible pad for nasal cannula, as shown and described.

DESCRIPTION

FIG. 1 is a top, front and side perspective view of a flexible pad for nasal cannula embodying my new design;

FIG. 2 is a front elevational view thereof, the rear elevational view being a mirror image;

FIG. 3 is a left side elevational view thereof, the right side elevational view being a mirror image;

FIG. 4 is a top plan view thereof; and,

FIG. 5 is a bottom plan view thereof.
